UNITED STATES PATENT OFFICE.

AMBROSE J. GUIDRY, OF NEW ORLEANS, LOUISIANA, ASSIGNOR TO FINLAY DICKS & CO. LTD., OF NEW ORLEANS, LOUISIANA.

DESIGN FOR A DOME-TOP TOILET-POWDER CAN.

44,100.

Specification for Design.

Patented May 27, 1913.

Application filed July 1, 1912. Serial No. 707,109. Term of patent 14 years.

To all whom it may concern:

Be it known that I, AMBROSE J. GUIDRY, a citizen of the United States, residing in New Orleans, in the parish of Orleans and State of Louisiana, have invented a new, original, and ornamental Design for a Dome-Top Toilet-Powder Can, of which the following is a specification, reference being had to the accompanying drawing, forming part hereof.

Figure 1 is a side view of a can showing my new design. Fig. 2 is a plan view of the same.

The body of the can is cylindrical and it is surmounted by a bulbous top whose greatest diameter is adjacent to its upper end, and such top is in turn provided with a conical ornamental cap.

I claim:

The ornamental design for a dome-top toilet-powder can, as shown and described.

AMBROSE J. GUIDRY.
